UNITED STATES PATENT OFFICE.

JOHN WALTER MAY, OF CAMBRIDGE, MASSACHUSETTS, ASSIGNOR, BY DIRECT AND MESNE ASSIGNMENTS, TO MAY UNIVERSAL LAST CORPORATION, OF BOSTON, MASSACHUSETTS, A CORPORATION OF MASSACHUSETTS.

LAST.

Application filed June 10, 1922. Serial No. 567,341.

This invention relates to sectional lasts of that type which comprise a fore part and a heel part connected together to move toward and from each other for the purpose of shortening or expanding the last, an intermediate part situated between the fore part and movable in one direction so as to permit the last to contract or shorten and when the last is lengthened movable into a position to hold the fore part and heel part separated, and a lock for locking the intermediate part in its operative position.

A last having this general construction and principle of operation is disclosed in my Patent No. 1,496,091, dated June 3rd, 1924.

One of the objects of my present invention is to provide a novel connection between the fore part and heel part which will retain the two parts of the last in proper relative position as the last is expanded or contracted and which will also withstand any strain to which the last is subjected when in use.

Another object of the invention is to provide an improved form of lock for locking the intermediate part in its operative position which will also withstand any strain to which the last may be subjected when in use.

Still another object of the invention is to provide an improved means for supporting the last while in use and otherwise to improve lasts of this character all as will be more fully hereinafter set forth.

In order to give an understanding of the invention I have illustrated in the drawings a selected embodiment thereof which will now be described after which the novel features will be pointed out in the appended claims.

Figs. 1 and 2 are sectional views of a last embodying my invention, Fig. 1 showing the last lengthened and Fig. 2 showing the last shortened.

Fig. 3 is a section through the connecting member on the line 3—3, Fig. 1.

Fig. 4 is a section on the line 4—4, Fig. 1.

Fig. 5 is a view showing the position of the last in use and illustrating the means for supporting the intermediate section of the last.

Fig. 6 is a top plan view of the supporting member.

Fig. 7 is a section on the line 7—7, Fig. 5. The last shown in the drawings is a sec-

tional last and comprises the fore part 1, the heel part 2 and the intermediate part 3. 55

In making the last the last block is divided along the lines 4 and 5 so that the intermediate part 3 is wedge-shaped as shown. The fore part and heel part are connected by a telescopic connection which permits them to move toward and from each other all as described in my above-mentioned patent.

When the intermediate part is in its operative position shown in Fig. 1 the last is extended while when the intermediate part is moved transversely into the position shown in Fig. 2 the last may be shortened by a relative movement of the fore part and heel part toward each other. 65

One feature of my present invention relates to the construction of the telescopic connection between the fore part and the heel part. This comprises one member 6 which is anchored in the fore part, another member 7 anchored in the heel part. The member 6 has an anchoring portion 8 which occupies a slot formed in the rear face of the fore part 1 and which is retained in said fore part by means of pins 9 that are driven transversely through the last and through the anchoring portion 8. This member 6 is also provided with a rearwardly-extending arm 10 which has a telescopic relation with a portion of the connecting member 7. The member 7 is also formed with the anchoring portion 11 which occupies a slot in the front face of the heel part 2 and is retained therein by pins 12 driven transversely through the heel part and said portion 7. This portion 7 is also formed with the forwardly-extending arm 13 which is tubular in shape and which receives the arm 10. the latter telescoping into the tubular arm 13. 70

The arm 10 is provided with a pin 14 extending transversely therethrough, the ends of which operate in slots 15 formed in the side walls of the tubular arm 13, said pin and slot serving to limit the telescopic movement of the connection. 75

The intermediate part 3 is provided with a slot or opening 16 extending from the front to the rear thereof in which the telescoping arms 10 and 13 are received, said slot having a vertical dimension considerably greater than that of the telescoping arms so as to 80 permit the intermediate member 3 to move

from its operative position shown in Fig. 1 to that shown in Fig. 2.

The dimensions of the arms 10 and 13 are considerably greater in a vertical direction than in a transverse direction and by means of this construction a telescopic connection is provided which will maintain the fore part and heel part firmly in true relation to each other in all relative positions thereof. Furthermore the manner of constructing the members 6 and 7 and anchoring them in the last is such that they will withstand any severe strain to which the last is subjected in use.

15 A lock is provided for locking the intermediate part in its operative position as seen in Fig. 1, said lock being similar to that shown in my above-mentioned patent. This lock comprises a latch 17 carried by the intermediate part 3 and acted on by a spring 18 tending to throw it forwardly, and a keeper 19 set into a recess in the face of the heel part 2 and having an aperture 20 to receive the end 21 of the latch. The heel part is shown as provided with a latch-releasing plug 22 operable in a recess 23 formed in the heel part and adapted when moved to the left in Fig. 1 to engage the latch and release it from the keeper 19. This latch-releasing member 22 can be actuated through an opening 24 in the wall of the usual thimble 25 that is located in the heel part, all as described in my above-mentioned patent.

20 When a last of this type is being used, especially in the sole-levelling process of manufacturing the shoe, there is heavy pressure applied to the sole of the last and in order to provide a lock which will withstand any such pressure.

25 I propose to anchor the keeper 19 to the connecting means by which the fore part and heel part are connected. In the present embodiment of the invention this is accomplished by forming the keeper with an opening 26 through which the tubular arm 13 extends, and with this construction any strain on the keeper due to pressure on the bottom of the intermediate section of the last will be transmitted directly to the connecting members 6, 7, which are firmly anchored in the fore part and heel part. With this construction, therefore, there will be no danger that any pressure on the bottom of the intermediate part will loosen the keeper from the heel. The connecting member 7 is shown as having a notch 27 in which the lower edge of the keeper is received.

30 In order to still further stiffen the last when it is in its operative or lengthened condition I have made the connecting member 6 with the extension 28 which operates in the slot 16 of the intermediate part and which has a recess 29 adapted to receive a pin 30 anchored in the intermediate part when the latter is in its operative position as shown in

Fig. 1. This pin 30 and the extension 28 cooperate to prevent the intermediate part and the fore part from separating at the top of the last. When the last is in use the heavy pressure on the bottom of the last has a tendency to separate the intermediate part and fore part at the instep portion of the last but such tendency is counteracted by the engagement of the pin 30 in the extension 28.

35 In using a last of this type during the sole-levelling operation it is desirable to provide means for furnishing a support to the intermediate part 3 as well as to the heel part 2.

40 In Figs. 5, 6 and 7 I have shown how this may be done. In Fig. 5, 40 indicates a portion of the jack on which the last is sustained and 31 is the last pin adapted to enter the thimble 25.

45 The proper support for the intermediate part is furnished by a supporting member 32 which has a slot 33 to receive the last pin 31 and which has a flat face 34 on which the heel part 2 rests. This supporting member 32 is of a dimension to extend underneath the intermediate part 3 and it is also provided with a recess 35 of a shape to receive the point 36 of the intermediate part. The recessed end of this supporting member which engages the intermediate part 3 is supported directly on the jack 40 and for this purpose it is formed with an inclined extension 37 which carries an adjusting screw 38 having a notched end 39 adapted to engage the corner of the jack 40. This adjusting screw 38 is screw-threaded through a nut 42 carried by the extension 37 so that by turning the nut 42 the screw 38 can be projected or withdrawn thereby supporting the member 32 at the proper angle.

50 41 indicates a toe pad to support the toe of the last. In using this supporting member 32 it will be placed over the last pin before the last is applied thereto and when the screw 38 is properly adjusted the intermediate part 3 will have a solid support in the recess 35. When this supporting member is used the severe strain to which the last is subjected during the sole-levelling or other similar operations will be taken by the supporting member 32 and transmitted direct to the jack thus relieving the telescopic connection and lock from such strain.

55 I claim:

1. A last comprising a fore part and a heel part connected to be moved relatively toward and from each other thereby to shorten or extend the last, means for connecting said parts to permit such movement, and a lock for locking the last in extended condition, said lock including a latch and a keeper with which the latch co-operates and which is anchored to the connecting means.

2. A last comprising a fore part, a heel part, a wedge-shaped intermediate part

- movable transversely of the last, connecting means between the fore part and heel part which permits them to move toward and from each other as the intermediate part 5 moves transversely, a latch carried by the intermediate part, and a keeper for the latch carried by the heel part and anchored to the connecting means.
3. A last comprising a fore part, a heel part, an intermediate part capable of movement transversely of the last, a telescopic connection between the fore part and heel part which permits them to move relatively toward and from each other as the intermediate part moves transversely, a spring-pressed latch carried by the intermediate part, and a keeper for the latch carried by the heel part and anchored to the telescopic connection.
4. A last comprising a fore part, a heel part, an intermediate part movable transversely of the last, a telescopic connection between the fore part and heel part, said connection comprising a tubular member anchored in one part and a complementary member anchored in the other part and having a tongue sliding in the tubular member, and a lock for locking the last in extended condition, said lock being so constructed as to transmit the strain to which it is subjected to the said connection.
5. A last comprising a fore part, a heel part, a telescopic connection between said parts which permits them to move toward and from each other in the direction of the length of the last, movable means situated between said last parts to hold them in their extended position, said connection comprising a member anchored in one part and having an arm, and another member anchored in the other part and having a tubular arm into which the first-named arm telescopes, said arms having co-operating means limiting their telescoping movement in one direction and a lock to hold the last in extended position, said lock comprising a member carried by said movable means.
6. A last comprising a fore part, a heel part, a telescopic connection between said parts which permits them to move toward and from each other in the direction of the length of the last, and movable means situated between said last parts to hold them in their extended position, said connection comprising a member anchored in one part and having an arm, and another member anchored in the other part and having a tubular arm into which the first-named arm telescopes, said arms both having a greater dimension in a direction vertically of the last than horizontally of the last, said tubular arm having a slot and the other arm having a projection operating in said slot.
7. A last comprising a fore part, a heel part, a wedge-shaped intermediate member capable of movement transversely of the last,
- capable of moving transversely of the last, a telescopic connection between the fore part and heel part, said connection comprising two members one of which is anchored in one of said parts and is provided with an arm rectangular in cross section with the longer diameter extending at right angles to the bottom of the last, said arm having a lateral projection, and the other of which members has a tubular portion in which the arm telescopes and which has a shape to fit the arm, said tubular portion having a slot to receive said projection.
8. A last comprising a fore part, a heel part, a connection between said parts which permits them to move toward and from each other without changing their angular relation, movable means situated between said parts to hold them in their extended position, said connection comprising a member having an anchoring portion anchored in a groove in the rear face of the fore part and also having a rearwardly extending arm, the dimension of said anchoring portion vertically of the last being greater than the corresponding dimension of said arm, and a co-operating tubular member anchored to the heel part and having a telescopic relation with said arm.
9. A last comprising a fore part, a heel part, a connection between said parts which permits them to move toward and from each other without changing their angular relation, movable means situated between said parts to hold them in their extended position, said connection comprising a member having an anchoring portion set into a groove in the rear face of the fore part and also having a rearwardly-extending arm, and a co-operating slotted tubular member anchored to the heel part and having a telescopic relation with said arm, the latter having a projection operating in the slot of the tubular member.
10. A last comprising a fore part, a heel part, a wedge-shaped intermediate member movable transversely of the last, a connection between the fore part and heel part which permits them to move toward and from each other without changing their angular relation, said connection comprising two members each having an anchoring portion set into and anchored in a groove in one of the last parts, one of the members having a tubular arm extending toward the other member and the other member having an arm telescoping in the tubular arm, the dimension of each anchoring portion in a direction vertically of the last being greater than the corresponding dimension of the tubular arm, and means to limit the telescoping movement of said arms.
11. A last comprising a fore part, a heel part, a wedge-shaped intermediate member capable of movement transversely of the last,

4
a connection between said fore part and heel part which permits them to move toward and from each other, said connection comprising a member anchored in the fore part and having a rearwardly-extending arm, another member anchored in the heel part and having a forwardly-extending tubular arm into which the first-named arm telescopes, the member anchored in the fore part having a notch, and a pin carried by the intermediate part to engage said notch when the last is in extended position.

12. A last comprising a fore part and a heel part connected to be moved relatively toward and from each other thereby to shorten and to expand the last, a wedge-shaped intermediate part situated between the fore part and heel part and movable transversely of the last, means to lock the intermediate part to the heel part, and other means for connecting the intermediate part to the fore part when the last is lengthened thereby to prevent separation of said parts at the instep of the last in a direction longitudinally of the last.

13. A last comprising a fore part and a heel part connected to be moved relatively toward and from each other thereby to shorten and to expand the last, a wedge-shaped intermediate part situated between the fore part and heel part and movable transversely of the last, means to lock the intermediate part to the heel part, and other means adjacent the instep portion of the last for connecting the fore part to the intermediate part when the intermediate part is in operative position with the last lengthened, said means operating to prevent the fore part and intermediate part from separating in the direction of the length of the last.

14. A last comprising a fore part, a heel part, a wedge-shaped intermediate part movable transversely of the last, connecting means between the fore part and heel part which permits them to move toward and from each other as the intermediate part moves transversely, a hook rigid with the fore part and a pin carried by the intermediate part and adapted to engage said hook when said intermediate part is in its operative position.

15. A last comprising a fore part, a heel part, a wedge-shaped intermediate member movable transversely of the last and a telescopic connection between the fore part and heel part, said connection comprising two members, one of said members having an anchoring portion anchored in one of said parts and also having an arm extending longitudinally of the last, said anchoring portion having a greater dimension vertically of the last than said arm, and the other of said members anchored in the other part of the last and having a tubular portion with which the arm telescopes.

16. A last comprising a fore part, a heel part, a wedge-shaped intermediate member movable transversely of the last and a telescopic connection between the fore part and heel part, said connection comprising two members, one of said members having an anchoring portion extending vertically of the last and anchored in one of said parts and also having an arm extending longitudinally of the last, and the other of said members having an anchoring portion also extending vertically of the last and secured to the other last part, said other member having a tubular portion extending longitudinally of the last and into which the arm telescopes, the dimension of each of said anchoring portions in a direction vertically of the last being greater than the corresponding dimension of said tubular portion.

17. A last comprising a fore part, a heel part, a wedge-shaped intermediate member capable of moving transversely of the last, a telescopic connection between the fore part and heel part, said connection comprising two members, one of which has an anchoring portion extending vertically of the last and anchored in one of said parts and provided with a tubular portion and the other of which is in the form of an arm anchored in the other part of the last and telescoping in said tubular portion, the dimension of said anchoring portion in a direction vertical of the last being greater than the corresponding dimension of the tubular portion.

In testimony whereof, I have signed my name to this specification.

JOHN WALTER MAY.
